PROJECTILE FUZE SETTING APPARATUS**Ernest F. Campbell, Springfield, Va., Philius H. Girouard, Washington, D. C., and Alvin E. Cohen, Chicago, Ill.****Application December 13, 1951, Serial No. 261,572****2 Claims. (Cl. 89—6)****(Granted under Title 35, U. S. Code (1952), sec. 266)**

This invention pertains to a naval type gun turret and more specifically to a new and novel fuze setting control system and to the novel structure and arrangement of parts thereof whereby the handling of the projectile increment of the ammunition load is such as to provide fully automatic fuze setting in the cradle assembly of the hoist loading system. This fuze setting during transfer from a hoist position to a transfer position at the gun slide permits more rapid handling and firing of large bore guns than that of large bore guns of similar size heretofore in use. The projectile increment fuze setting equipment and control equipment, therefore, of this invention is well adapted for use with a rapid fire gun and turret arrangement of a type as shown, for example, in the copending application to Philius H. Girouard et al., Serial No. 153,262, filed March 31, 1950. The subject matter of this invention is shown and partially described but not claimed in the above mentioned copending application to Girouard et al.

Heretofore, naval turrets mounting large bore guns have incorporated therein in their apparatus and method of operation the usage of a bag type powder charge for the propulsion of the projectile from the gun. In some smaller bore applications the use of fixed pre-packed cased ammunition has been utilized to advantage but in large bore applications such fixed ammunition is extremely heavy and presents some disadvantages in handling. The gun turret system of the type for which this cradle fuze setting arrangement is adapted incorporates the use of semi-fixed ammunition wherein the projectile is handled by a system separate from that of the system handling the powder case. In large bore applications where projectiles have been handled by hoist systems and transferred to a position where they can be manually or otherwise handled for loading into the gun breech, the fuze setting has not been conveniently handled automatically by the control systems therefor while the projectile was in transfer movement, or in a position immediately prior to its movement for transfer.

The guns incorporated in the mount of the turret with which the present invention is associated are well adapted for use with semi-fixed ammunition rather than the powder bag type of ammunition previously used in guns of similar large bore. The incorporation of the semi-fixed cased ammunition therein as handled by the structural embodiment of this type of turret makes provision for the reception of two load increments, viz., a projectile, and a powder case at positions respectively on each side of the gun slide assembly. Ammunition increments received at the side of the gun slide are loaded into transfer trays of the gun loading system and are thereafter transferred to a firing position in the gun barrel. The projectile increment is stored in a storage chamber below the gun deck and is moved upwardly to a position adjacent the gun slide by a projectile hoist system. The upper portion of the cradle unit is a portion of the hoist and also is an enclosure for the projectile fuze setting system of this invention.

2

Throughout the transfer movement of the projectile and the powder case the increments follow a predetermined sequence of travel in order that the position of each increment with respect to the other increment be at all times correlated and be such that ramming action applied at the gun barrel to the powder case will also produce ramming movement of the projectile forwardly thereof into the gun breech. In such an arrangement it is essential that any fuze setting operation not delay the sequence or order of the cycle. It is, however, desirable on occasion to have the fuze setting operation take place at the last possible instant prior to gun firing. Such provision is accomplished by the control system of the turret with which this fuze setting equipment is adapted for use. In such a system, fuze setting may be held up in the cradle and the projectile increment retained until the desired range information is fed into the input of the receiver-regulator of the fuze setter. Immediately after fuze setting takes place, the projectile is released by the ram-spring assembly of the projectile cradle and is ram-ejected into the transfer tray for subsequent transfer to the projectile and powder case aligned-ramming-position rearwardly of the gun breech.

The drive assemblies which move the fuze mechanism 25 of the projectile are enclosed by, and movable with, the projectile cradle and thus can accomplish fuze setting at any position in their path of travel or after the cradle has come to rest in its latched position on the gun slide. The fuze setting receiver-regulator assembly associated 30 with the drive for the fuze setter is also mounted on the projectile cradle for movement therewith. The receiver-regulator may advantageously be of the type shown in U. S. Patent 2,444,813, issued July 6, 1948, to F. W. Cunningham. This fuze setting equipment which comprises a fuze setter and a fuze setting receiver-regulator assembly is remotely controlled, and is arranged in a power driven installation embodying an automatic setting-power drive type fuze pot device for use with nose-type mechanical time fuzes. The receiver-regulator embodies an electrical amplifier, an electrical output regulator, and an electric power driving motor.

The fuze setter is mounted within the upper tubular 45 portion of the projectile cradle and has its component sub-assemblies arranged therein in a manner wherein the A-unit or the receiver-regulator is mounted on the forward side of the cradle and the B-unit or amplifier assembly may be mounted on the bulkhead structure of the gun pocket.

The arrangement of the fuze setter outer housing is 50 such as to serve as a guide for the cradle ram spring of the cradle and encloses the fuze pot assembly, which comprises the holding cup and setting cup associated with the differential drive mechanism therefor. All of these 55 component units are separate from the outer housing groups which comprise the drive and gear mechanism, the input coupling and the fuze pot retracting mechanism. The fuze pot retracting mechanism is mounted on the cradle to provide disengagement of the fuze setter in the event that the ammunition being fired is not of a fuze set variety.

One object of the present invention resides in the provision of a fully automatic fuze setting arrangement for setting the fuzes of mechanical fuze-type projectiles and 60 an electrical control system therefor in which many of the foregoing disadvantages are obviated and which is adapted to perform satisfactorily all of the essential functions of the systems heretofore or now in general use, and in which the possibility of mis-setting fuzes or apparatus malfunction is reduced to a minimum.

An additional object of this invention lies in the provision of a rapid fire rate projectile fuze setter in an ar-

angement for assembly in the cradle of the gun loading system.

Another object of this invention lies in the provision of a cradle assembly adapted to provide fuze setting at any point along the path of travel of the cradle in its movement from the projectile hoist to the gun slide.

An additional object of this invention lies in the attainment of new and improved fuze setting in a gun loading cycle which is accomplished remotely and by mechanical means without manual intervention.

Another object of the invention lies in the accomplishment by improved means of projectile fuze setting from an information source external to the gun assembly.

It is an additional object of this invention to provide projectile fuze setting in synchronized time relationship with the loading and handling of a powder case whereby both the powder case and the projectile are available as needed at the gun loading station to maintain uninterrupted operational loading and firing sequence, while preventing premature projectile release prior to the completion of fuze setting.

In correlation with the immediately preceding object regarding simultaneous loading of projectiles and powder case increments, it is an additional object of this invention to provide fuze setting which may be delayed up until the last stage of the gun loading and thus immediately prior to gun firing.

Another object of the invention is the provision of a new and improved control means to permit projectile-fuze-setting operations from a location remote from the operating mechanism of the turret and wherein an initial setting of the fuze may be changed after movement to a position at the gun slide to make corrections for changes in the path of travel of the target in the event some delay exists between the time of projectile cradle movement and the instant when gun firing is desired, while maintaining a constant dead time therefor.

Additional objects and advantages of this invention will be apparent from the following description of a preferred embodiment and the same will be readily appreciated as they become better understood by reference to the following detailed description of the preferred embodiment of the instant invention and the accompanying drawings wherein:

Fig. 1 is a generally schematic diagram of the fuze setting control circuit and shows the component control assemblies thereof;

Fig. 2 is a fragmentary view partially in section showing the upper cradle arrangement for the mounting of the fuze setter and showing further the manner in which the fuze pot is adapted for engagement with a nose type projectile fuze;

Fig. 3 is a fragmentary view partially in section showing the drive gearing arrangement for the fuze pot;

Fig. 4 is a partially fragmentary view showing the fuze setter retractor mechanism and the means of operating it from equipment associated with and mounted on the projectile cradle;

Fig. 5 is a view showing the general arrangement of the fuze setter receiver-regulator unit as assembled in a gun turret for use therewith;

Fig. 6 is a generally schematic diagram of the gearing arrangement of the fuze setting equipment;

Fig. 7 is a schematic wiring diagram of the fuze setting receiver-regulator amplifier;

Fig. 8 is a schematic wiring diagram of the electrical system and showing certain assemblies thereof in block form, with the switch circuit thereof set in "Run" position;

Fig. 9 is an operational diagram of the fuze setting equipment cycle and shows the functional purpose of the various elements of the assembly and their associated relationship with all of the other elements, and

Fig. 10 is a schematic wiring diagram of the complete electrical circuit of the fuze setting system.

The mechanical-time fuze for which the apparatus of the instant invention is intended is illustrated generally in Fig. 2 wherein the projectile is shown at 12. The nose portion at 7 is rotatable with respect thereto, and is provided with a notch for reception of pawl 16 of the setting cup. The rotatable fuze portion includes the time calibrations shown in the drawing while the fixed part is that portion therebelow. The fixed part includes a recessed notch or the like for reception of the holding dog or pawl at 14. The internal construction is such that rotation of the nose portion 7, with respect to the fixed part on the projectile, through an angle representing fuze order produces the desired time setting.

Referring now to Fig. 1 of the drawings, the fuze setting receiver-regulator shown generally at 1 is mounted on a rear portion of the projectile hoist cradle assembly 2, for movement therewith from a cradle loading position at the hoist to a cradle discharge position at the gun slide for ejection of the projectile into transfer trays 20 of the gun system. The cradle is pivotally mounted by suitable trunnions at 4 to provide this movement. The fuze pot assembly which is adapted to engage the projectile is shown at 5 and is arranged with a retracting mechanism 6 for engagement with the nose 7 of the projectile 12 or for disengagement from the projectile in the event the projectile increment to be fired is not of a fuze-set variety. The arrangement of Fig. 1 additionally includes a regulator amplifier 9. The entire system is associated with the gun captain's control panel 8 and the turret officer's transfer switchboard 11.

Referring now to Fig. 2 of the drawings the projectile is shown at 12 in engaged relationship with the projectile guide cup 13 which is a part of the projectile cradle. Adjacent thereto is a rotatable fuze holding cup 3 wherein, the fuze holding slot of the fuze, is engaged by a holding dog 14 thereof. The fuze setting cup 15 is provided with a setting dog 16 for engagement with the rotatable portion of the projectile fuze. The setting cup 15 is a rotatable assembly suitably mounted by bearings 55, Fig. 3, and 18, Fig. 2. The fuze holding cup assembly 3 which carries the holding dog 14, is suitably mounted on bearings 17 and 20. Bearing 20 is mounted in the fuze setter head 3 and serves as a support for bearings 18. Seals 19 and 21 are provided for the purpose of limiting oil leakage from the differential drive assembly associated therewith. The positioning device 22 is arranged interiorly of the ram or ejection spring 23 of the cradle. It is mounted on the projectile guide cup 13, in a manner to maintain the fuze setter in contact with projectiles of various lengths, and functions to position the guide cup 13 in axial relation to the fuze holding cup 3. The fuze setting cups and the dog elements associated therewith are driven from a power source 10 in the receiver-regulator by power applied through a coupling 24 which comprises the coupling hub 25, a coupling disc, and an upper coupling hub 26 of Fig. 3.

The coupling is spline-shaft mounted to the input gear 27 which is suitably mounted by bearing elements 28 for rotation in the gear case 29. An idler gear 30 is suitably mounted on a bearing assembly 31 for engagement with the driving gear 32. This driving gear is mounted between parallel ball bearing assemblies 33 and 34 and is arranged to drive an internal spur gear hub 35 having a sliding spur gear 36 arranged therewith. The sliding spur gear 36 is mounted on the shaft 35 by means of a key 37 in the keyway 38 and a locknut at 39, and is arranged at its opposite end to be rotatably mounted in the bearings 40. Near the lower end of the shaft, there is a pinion at 41 to rotate the ring gear 42 which is in engagement therewith and adapted on its inner surface to receive and support a pair of lower spider bevel gear elements 43 and 44. The bevel gears are arranged in an assembly to engage and drive the lower bevel gear member 45, Figs. 3 and 6, which is an integral part of the holding cup assembly 3. An inter-

mediate bevel gear 53 is a double gear, having one gear 46 thereof arranged to engage the opposite surfaces of the small bevel gears associated with the ring gear and is mounted in a parallel arrangement with respect to the lower bevel gear of the holding cup. The rotatable mounting for the spider bevel gears 43 and 44 is provided by a shaft and bearing assembly located at one side of 47. The intermediate bevel gear 53 is arranged to drive a pair of fixed bevel gears 48 and 49 which are rotatably mounted in a fixed position by means of the bearing assembly 50 which is arranged to receive the stub shafts 51 and 52 (not shown) of these fixed bevel gears. The fixed bevel gears which are driven by the intermediate bevel gear 53 are arranged to prevent unit rotation of the differential assembly and to impart rotation to the upper bevel gear 54 which in turn is mounted for rotation in the bearing 55 and is arranged to drive the setting cup drive 56 of the assembly. The drive is provided through a shaft and hub assembly 57 of Fig. 6 which is arranged internally of the bevel gears and the intermediate bevel gear 53 and extends downwardly to the upper end of the setting cup assembly 15.

A bayonet joint 58 is provided in the upper fuze pot housing cover 59 for reception of the retract shaft 60 of the fuze pot retractor assembly 6. This retract shaft may be enclosed by a fuze pot tension spring 61. It is arranged to extend upwardly through a support mounting 62. Alternatively, the preferred embodiment incorporates a pair of springs 61 spaced on each side of the shaft 60. One of these springs 61 is shown behind the shaft 60 in Figs. 3 and 4. The linkage assembly for retracting the fuze pot is as shown in Fig. 2 and Fig. 4 and includes a link shaft 63 connected to the retract shaft pivot 64. The link shaft 63 is pivotally connected at 65 to a bell crank 66.

The bell crank is mounted on the support structure 67 of the cradle 2 and is connected at the opposite end thereof to a handle driven sliding yoke link 68 which in turn is pivotally connected at 69 to the pivotally mounted handle 70. The handle is mounted on the upper frame structure of the cradle and is pivotally mounted at 71 by a pin 72 which extends through the lower portion of the handle 6. This handle-lever arrangement is provided with a detent at 73, not shown, for the purpose of maintaining the handle in a locked or in locked-out position for the fuze pot.

The fuze pot drive assembly at 1, Fig. 2, which drives the differential gear assembly for holding and setting the fuze is preferably constructed as a separate unit and is arranged to have the output shaft 74 thereof of Fig. 6 arranged for engagement with the coupling hub 25 of the gear drive assembly. As shown in the schematic diagrams of Fig. 1 this output shaft of the fuze setter receiver-regulator serves as the input to the gear train for the fuze pot.

Referring now to Fig. 6 the fuze setter receiver-regulator comprises a regulating drive system, an indexing drive system and an output drive system which cooperate to provide an output through shaft 74. In addition to these drive systems the gearing illustration includes a showing of the fuze setter input drive which is connected to shaft 74 by coupling 24, as hereinabove described. The regulating drive is placed in operation by means of a regulating motor 75 having a spur gear 76 mounted on the shaft extension 77 thereof. This spur gear is arranged to drive the pinion gear 78 which in turn is coupled by the shaft 79 thereof to a spur gear 80 and to a bevel gear 81. The spur gear 80 is arranged to drive its mating gear 82 and provide output energy for the output drive element. Control of the output regulating drive is provided by a control transformer 83 having its shaft 84 arranged with a gear 85 thereon and in engagement with a gear 86 which is driven by the bevel gear 87 through shaft 88. The upper end of shaft 89 is provided with a bevel gear 90 for mating engagement

with the bevel gear 81 of shaft 79. The control also includes a velocity dampening generator 91 arranged to be driven by gear 92 through gear 78 to the shaft 93 thereof.

5 The indexing drive assembly generally designated 94 for positioning the fuze holding cup and its dog initially prior to fuze setting is controlled by the indexing motor 95 having a clutch assembly 96 connected to the output shaft 97 thereof. This clutch is arranged to drive through the disc 98 to the driven disc 99 of shaft 100 which has a gear 101 on the output end thereof. A brake shoe 172 and a brake member 173 are arranged for engagement with the driven disc 99 of the clutch 96. The motor output gear 101 is connected in engaged relationship with a gear 102 to drive a gear 103 of the shaft 104 and is additionally arranged with a pinion 105 on a shaft 106 thereof for engagement with a gear 107, which in turn drives through a train of gears 108 and 109 to a shaft 110 on which are mounted the indexing cam 111 and the brake cam 112. These cam members are arranged in a manner to operate a brake auxiliary switch 113 and an indexing switch 114 of the control system for the unit.

25 The shaft 104 which is driven by gear 103 has a bevel gear 115 mounted on one end thereof for engagement with a differential bevel gear assembly at 116. This differential assembly is arranged to drive the output drive, and as hereinabove set forth is driven by the regulating drive through gear 82 of shaft 117, and the bevel gear 30 118 as well as by the indexing drive 94 through the above recited bevel gear 115.

35 The output of the system which drives the adjustable coupling 24 and which receives drive energy imparted by either the regulating drive at 82 and 116 or the indexing drive at 103 through the differential 116 is arranged with a shaft 119 connected to the spider of the differential unit and to a gear 120. Gear 120 is arranged to drive through an idler gear 121 to the output gear 122 of shaft 74 for the adjustable coupling 24. The shaft 40 119 on which the gear 120 is mounted, additionally includes a pair of spur gears 123 and 124 on the shaft thereof. The gear 123 is arranged to drive through gear 125 to the shaft 126 of a control transformer 127. The gear 123 additionally drives the pinion 128 to implement rotation through the shaft 129 to a bevel gear 130 of the right angle gear assembly at 131. This gear assembly drives through its shaft 132 the bevel gear 133 and the bevel gear pair 134 and 135. The bevel gear 134 is arranged to drive the high speed check dial 136 by means of a gear assembly 137 and shaft 138. The bevel gear 135 which is also driven by bevel gear 133 has a worm 139 and worm wheel 140 arrangement to drive the low speed check dial 141 and the minimum fuze setting cam 142 mounted on the output of the shaft 143 thereof. 45 50 55 This cam is arranged to engage the minimum fuze setting switch 144. The gear 124 on shaft 119 is arranged to drive through an idler gear 145 to a gear 146 of the control transformer 147.

60 The operational arrangement of the schematic system as hereinabove described is set forth for purposes of illustration but is not necessarily limited to the particular gear and shaft arrangement illustrated in Fig. 6. The arrangement of the fuze setter elements as hereinabove described is such that the fuze setter outer housing 65 serves as a guide for the cradle ram spring 23, Fig. 2, and encloses the fuze pot assembly 5. The fuze pot assembly comprises the holding cup, a setting cup and a differential drive mechanism. All other components comprising, the driving gear mechanism, the input coupling, the fuze pot retracting mechanism and the inner-lock switches, are separate from the outer housing group and are mounted on the cradle bracket.

70 The A-unit Fig. 5 of the regulator 1 is a water-tight case enclosure with its interior components arranged in a chassis type assembled relationship with three access

covers at 148, 149 and 150. They comprise the terminal tube access 148 in the front, a terminal block and drain access 149 in the bottom and a main access cover and a dial window forming the back 150. The main chassis 151 of the unit supports the indexing motor, the dial assembly, the differential 116, the minimum fuze setting cam and switch, and a portion of the instrument gearing. The interior details not shown include a sub-chassis and a lower chassis. The sub-chassis therein is mounted on the rear of the main chassis and provides a mounting for the regulating motor, the synchro control transformers, the velocity damping generator, the indexing and brake auxiliary cams, and the indexing and brake auxiliary switches. These main units of the receiver-regulator for operation of the fuze setter are hereinafter designated as the A-unit 1, which is the unit mounted on the forward side of the projectile cradle, and the B-unit or amplifier 9, Fig. 1 the assembly of which is mounted on structure of the gun pocket. The B-unit comprises an amplifier cabinet having therein a blower on motor M-3, Fig. 10, for cooling the chassis assembly units thereof.

The equipment of the A-unit main chassis group comprises the indexing motor 95 with the input magnetic clutch and brake elements at 96, the instrumentation gear mechanisms, the check dials 136, 141 and the minimum fuze setting cam and switch assembly 144. These elements are shown in block diagram form in Fig. 1 and with their power source interconnections, while the operational relationships therefor are illustrated in the gearing diagram of Fig. 6.

The general system for the electrical interconnections between the elements of the fuze setting equipment and the control switches of the gun captain's control panel is shown in Fig. 1. The several power supply sources are also indicated thereon. The system includes two external power supply sources, wherein the main power supply is 440-volts, 3-phase, 60-cycle current from the projectile hoist power controller, and the synchro supply is 115-volts, single-phase, 60-cycle current. These service currents are transformed and rectified for motor and amplifier supply by the transformer and vacuum tube rectifier units of the receiver-regulator system.

The fuze pot housing assembly which is enclosed by the cradle is retracted from the projectile engaging position by the linkage 63, 66, 68 connecting the retract handle 6 with the retract shaft 60, Fig. 3. The retract shaft slides in the fuze setter switch mounting bracket 62 and is connected to the fuze pot housing covered by the bayonet joint 58 as shown in Fig. 4. An O-ring 152 is mounted in the switch bracket to seal the retract shaft. As hereinbefore described, one end of the connecting linkage is secured to the end of the retract shaft 60 at 64, and the opposite end of the link is secured at 65 to one arm of the bell crank lever 66, which is mounted on the pivot pin 67 on the cradle bracket. An adjustable slotted clevis rod 68 connects the other arm of the bell crank lever 66 with a retract handle 6 on the upper flange 71 of the cradle bracket. The retract handle is pivotally mounted at 72 on the handle bracket whereby it may be locked either in the retracted position or in the normally extended position. This locking action is accomplished by a detent 153 which is a part of the handle knob 154. Detent holes are provided at 155 and 156 in the handle bracket for engagement by the detent when the handle is moved to the desired position.

The fuze pot housing is fully retracted when the retract handle is located in its upward position. Provision has been made for adjusting the retract mechanism by increasing or decreasing the effective length of the slotted clevis rod 68, by turning the rod into, or out of the clevis 157 that is pinned to the retract handle at 69. The slotted clevis 68 permits the retract handle to be locked at the "in" position while permitting the fuze setter head to be at variable distances of its movement.

This also permits the fuze setter head to translate when contacted by the projectile.

A pair of fuze setter regulator interlock switches are mounted in the assembly as shown at 158 on a switch mounting bracket 62 which additionally serves as a guide for the retract shaft 60 as shown in Fig. 4. The switch housing encases two sets of single-pole, double-throw contacts, which switches are controlled by the retraction or translation of the fuze pot assembly in the cradle. Two of the contacts of switches BZ-1, and BZ-2 of Fig. 10 are closed when the fuze pot housing is in its normally extended position, and the other two contacts are closed when the fuze pot housing has been translated by loading a projectile into the cradle. The switch plunger 159 is actuated by a pivoted, spring-loaded, switch lever 160 mounted below the switch on the switch mounting bracket 62. The taper at 161 is provided on the end of the retract shaft 60 to provide movement of the switch lever upwardly when the fuze pot housing is translated. The switch lever is spring returned when the fuze pot housing moves to its normally extended position and the portion engaging the taper drops to a reduced diameter section of the retract shaft.

The fuze setter is controlled from the gun captain's control panel by the fuze-setter regulator control switch which is a manually operated, 3-position, rotary type switch. This switch is provided for the purpose of energizing and deenergizing the fuze setter regulator control circuit as hereinafter set forth in greater detail.

When the switch is turned to a "run" position thereof, it functions to close the 115-volt, single-phase, 60-cycle projectile hoist supply to the relay BBR-3, Fig. 8. This closes contacts to connect the rectifier circuit for the indexing motor 95, the safe signal transformer 163 and the blower motor of the amplifier, to the 440 volt, 3-phase, 60-cycle, projectile hoist supply. In the run position thereof, this switch also connects the 115-volt synchro circuit to apply it to the regulator safety circuit, the primary of the generator field supply transformer T-8 of Fig. 10 and the bias circuit in the main field of the regulating motor. Additionally this switch when at its run position also connects the low and high-speed fuze setting order input for the stators of the control transformers with the plotting room source therefor.

A second position of the switch is a "safe" position, which functions when the selector switch is turned thereto to disconnect the incoming fuze setting orders from the plotting room, and connect the stators of the control transformers with a fixed signal. This is termed the safe signal, and it is derived from a safe signal transformer T-6 which drives the fuze to a safe position.

In the "off" position thereof the switch cuts out signal transmission to the fuze setting receiver-regulator and closes an additional circuit through GS-1 and GS-2 of Fig. 10 to bypass the fuze setting system in controlling projectile release from the cradle.

The indexing motor 95 in the regulator functions to rotate the dogs or pawls in the fuze setter far enough to insure their positive engagement in the slots in the projectile fuze. This action takes place immediately after the projectile enters the fuze pot. The mounted arrangement thereof in the main chassis of the A-unit is as illustrated in Fig. 1. The motor is a constant-speed, non reversible, fractional horse-power design operating on the 440-volt, 3-phase, 60-cycle current from the projectile hoist supply. The motor is designed to run continuously in the direction to decrease the fuze setting time whenever the selector switch BW on the gun captain's control panel is turned to "run" or "safe" position. This motor operates the indexing drive of the fuze setter as hereinbefore stated to provide three dead turns of the fuze setter cup in order that the dogs thereof will be positively engaged for any initial dog position with respect to the slots in the projectile nose when a mechani-

cal time-fuzed projectile is seated therein by the cradle ram. After the completion of three revolutions of the cup, the magnetic clutch 96 functions to disconnect the motor 95 from the indexing drive 94. Thereupon the magnetic brake disc surface 172 stops rotation of the indexing drive shaft 104 and consequently the application of power from this source to the differential 116. Other units of the fuze setting equipment thereupon take over performance of fuze setting operations.

A magnetic clutch and brake assembly 96 is mounted 10 between the indexing drive motor 95 and the indexing drive 94. The operative arrangement thereof is as indicated diagrammatically in Fig. 6. The clutch and brake assembly consists of a friction brake ring 172, a friction clutch disc 98, a friction drive disc 99, a magnetic clutch coil at 171 and a magnetic brake coil 173. The magnetic clutch coil is secured to the shaft extension end of the motor housing. The friction drive disc 98 is secured to the indexing motor shaft and is turned by the indexing motor. The friction clutch disc 99 is secured to the 20 output shaft 100 of the indexing drive and provides rotational energy for this shaft. The friction brake ring 172 is attached to the magnetic brake assembly which surrounds the indexing drive shaft and is secured to the brake coil housing assembly at the end of the housing. The indexing drive is that portion of the instrument shaft and gearing assembly which connects the indexing motor 95 with one end gear of the differential gear 115. The indexing drive functions to turn the fuze setter cups the necessary three dead turns to assure positive engagement of the fuze setting pawls in the slots of the differential fuze.

One end of differential 116 is supported on the main chassis 151, while the other end of the differential bracket is secured to the lower chassis. The differential 116 is mounted in such a manner that one end gear 118 of the differential is driven by the regulating motor 75, while the opposite gear 115 of the differential is driven by the indexing motor 95. The spider, or output shaft of the differential drives the fuze setter and the control transformers 147 and 127. The output shaft also drives the check dials and the minimum fuze setting cam 142 which operates the minimum fuze setting switch 144. The differential output, or spider shaft rotations of the differential produce the algebraic sum speed of the differential end gear inputs respectively from the regulating motor and from the indexing motor. During indexing operations the output of the regulating motor, which represents fuze setting order, is combined with the output of the indexing motor, representing the dead turns in a manner whereby the fuze setting corresponds to the fuze setting order at the completion of the dead turns. Subsequently, the output from the indexing motor is locked by means of the magnetic brake, and the differential output to the fuze setter is directly proportional to the regulating motor output. Thus the fuze is continuously maintained in synchronism with the fuze setting order until such time as the projectile is ejected from the cradle.

Two check dials 136 and 141 are geared to the receiver-regulator output drive and serve to indicate the fuze setting order in seconds of time. Their mounting arrangement in the instrument is such as to make them visible from the back portion of the fuze setter housing or forward with respect to the gun. The low speed check dial 141 is mounted on the minimum fuze setting cam 142 at the left side of the case of the A-unit. This dial is calibrated from 0 to 45 seconds in units of 0.2-second divisions. It is numbered at 0 and every 2 second interval from 1 to 45 inclusive; that is, 0, 1, 3, 5, 7, etc. to 45 seconds. The dial is arranged to have an S or "safe" indication at the "safe" position thereof. The high speed check dial designated as 136 is mounted to the right of the low speed dial and is engraved with a single crowfoot index mark. A rubberline is inscribed on an index dial plate between the two check dials. At

the electrical zero position of the output drive, the crowfoot index mark on the high speed dial is in alignment with the 10 second mark on the low speed dial and both marks are aligned with the rubberline.

The minimum fuze setting cam 142 hereinafter diagrammatically designated as CA-2 is mounted on the output drive at a position adjacent to the minimum fuze setting switch 144, schematically referenced SW-4 and is turned at low speed by the output drive and functions to control the operation of the minimum fuze setting switch. The switch 144 functions in connection with the regulator safety circuit to prevent the release of the projectile at any time when the rotational position of the output drive shaft is below a predetermined safe minimum fuze setting value. The minimum fuze setting switch is bracket mounted on a chassis assembly at a position directly below the low speed check dial 141. A roller 174 on the switch plunger is in alignment with the cam and arranged in a manner to be actuated by following the contour changes of the minimum fuze setting cam.

The regulating motor 75 serves as the fuze setting time control motor and is a reversible, variable-speed, fractional horsepower, two-phase induction type wherein one phase is connected to the 115 volt alternating current synchro supply and the other phase is connected to the output from the amplifier. The motor is arranged to provide operational output whenever the selector switch BW on the gun captain's control panel is turned to "run" or "safe" position. This motor is controlled by the error between the fuze setting order and the response from the regulator output shaft to the fuze setter. It functions to operate the regulating drive and maintain the angular displacement between the fuze setting dogs in synchronism with the incoming signal. The hereinbefore recited regulating drive is that portion of the instrument shaft and gearing which connects the regulating motor with one end gear 118 of the differential 116 as well as with velocity dampening generator 91 and the rotor of the control transformer 83. This regulating drive provides the function of maintaining the angular displacement of the fuze setter pulse in synchronism with the incoming synchro-signal. This arrangement is such as to provide both coarse and fine control and is adapted to operate with or without a projectile in the fuze pot.

The fuze setting system incorporates three synchro control transformers 147, 83, and 127 which function to control fuze setting through reception by the stators thereof of a synchro transmitted electrical fuze setting order wherein the rotors of the control transformers are driven by the output response of the regulating motor. The units function in such a manner that any difference between the position of the fuze setter drive and the signal received by the regulator produces an error voltage in the rotors of the control transformer. This error voltage is applied to the amplifier where it is amplified to a raised power level. Thereafter the amplifier output is applied to the control winding of the regulating motor in accordance with the fuze setting order.

The assembly also includes a velocity dampening generator 91 which is shown in the schematic diagram of Fig. 6 and which is mounted within the receiver-regulator case as shown generally in Fig. 1. This unit is driven by the regulating motor 75 and is arranged to introduce a dampening voltage into the signal circuit. This dampening voltage when applied to the amplifier with the error voltage, is proportional to the speed of the generator and opposes the error voltage. The dampening voltage tends to eliminate oscillation and overshooting and to cause smooth follow-up action. The velocity dampening generator is preferably a low-inertia, cup type induction device having both the main or exciting winding and the control field wound on the stationary stator. The bearing supported, cup type rotor encircles the sta-

tor. Both the rotor unit and the startor are cased within the generator housing.

In the operative relationship thereof the main field is excited by current flow from the generator field transformer shown schematically as T-8, to produce a resultant magnetic field which causes circulating currents to be set up in the rotor. These currents, in turn, produce a voltage in the control field of the generator which is proportional to the speed of the rotor. This voltage which is proportional to the rotor speed is utilized as the dampening voltage.

The indexing and brake auxiliary cams respectively designated CA-1, and CA-1A in Fig. 8, are mounted in spaced adjacency on the indexing drive cam shaft and in a manner wherein each respectively is separately and independently adjustable. The indexing cam and switch assembly at 111 coat with the brake auxiliary cam and switch assembly at 112 to control the indexing drive cycle by regulating the action of the magnetic clutch 96 and the magnetic brake coil 173. The switches associated with the indexing and brake auxiliary cams are provided with rollers 174, Fig. 6, which are aligned with and actuated by the contours of the respective cams.

The circuitry of the magnetic brake coil winding includes two resistances shown at R-49 and R-50 of the electrical circuit schematic drawing Fig. 10. The resistor R-49 is a coil resistor for the magnetic brake BM-1, and functions to limit the current to the coil 173 thereof to a normal amount required for brake operation. The resistor R-50 is used in the circuit to limit the brake current to a subnormal value which is insufficient to allow operation of the brake prior to the completion of the cycle. This arrangement allows quick brake application when the indexing cycle is completed.

The showing of the electrical circuitry additionally includes the blower motor designated schematically as M-3, used for dissipating heat from the amplifier, but which is not to be construed as an essential element of the inventive concept. It is a constant-speed, non-reversible, fractional horsepower unit mounted in the amplifier case to operate from the 440-volt, 3-phase, 60-cycle current source supplied by the projectile hoist power supply or any other suitable external power supply source. This motor is arranged in the circuit in a manner whereby it is designed to run continuously at all times when the selector switch BW, located on the gun captain's control panel, is turned either to the "run" or the "safe" position. It is directly controlled by action of relay BBR-3, through energization of the relay by the positioning of switch BW. This motor is connected to drive a squirrel-cage type blower unit for providing air circulation as a coolant for the elements mounted within the B-unit case.

The resistors R-46, R-47, and R-48 of the electrical schematic diagram comprise the impedance network of Fig. 10. They are strip heaters which are mounted within the amplifier case and function as regulating motor reactor resistors.

In the hereinafter described electrical circuit of Fig. 10 conventional designations are used wherein the prefix V indicates vacuum tubes, the prefix T transformers, C condensers, R resistors and CH chokes. Potentiometers used in the circuit are indicated by the prefix designation P.

In the hereinafter set forth description the connected relationship of all other electrical system components is set forth in a general manner only; the particular circuit terminal connections thereof being obvious to one skilled in the art, since it requires the mere following through of the line connections of the diagram. The vacuum tubes incorporated in the several circuits are thirteen in number and are designated as V-1 to V-13 respectively. Vacuum tubes V-1 and V-2 are connected to the low speed signal circuit, wherein V-1 is a pentode type of a commercial variety designated as a 6SJ7, and the tube V-2

is a twin-triode type similar to the commercial 6SN7 type. These two tubes are controlled by the coarse control error voltage and function to regulate the operation of the speed transfer relay designated RVY-1.

5 The vacuum tubes V-3 and V-4 of the circuit are connected to the high speed signal circuit in a manner whereby the fine-control error voltage controls the functioning of the tubes, and the tubes in turn regulate the operation of the synchronizing relay RVY-2. Similarly 10 as tube V-1, the tube V-3 is a pentode type of the commercial 6SJ7 variety while tube V-4 like tube V-2 is a twin triode of the type commercially designated as a 6SN7. These two sets of tubes function in a similar capacity in their respective vacuum tube relay systems hereinafter described in greater detail.

Vacuum tube V-5 is used as a class A voltage amplifier in a manner whereby it functions as the first stage of amplification of a four stage high gain amplifier. It is a pentode type commercially designated as a 6SJ7. 15 The tube operates in conjunction with the other tubes in the amplifier to supply control voltage of the primary of the driver transformer T-2 for control of the regulating motor 75. The twin-triode type tube V-6 is of the commercial type 6SL7 and functions as the second tube stage of amplification of the amplifier circuit wherein in the service thereof is as a phase inverter to the push-pull stage thereafter. The connection of this tube is such that the tube operates as two independent triodes enclose in the same envelope.

20 A pair of beam power pentode-type output tubes V-7 and V-8 of the commercial 6V6 variety are connected in the amplifier circuit to form the third stage of amplification. They function as class AB₁ push-pull amplifiers to supply the final push-pull stage of amplification. 25 The final stage of amplification incorporates a pair of power tubes V-9 and V-10 of the 811 variety which operate at a high power level as class B push-pull amplifiers to serve as the fourth or final output stage of amplification.

30 The power supply circuit of the amplifier incorporates the vacuum tube V-11 as a full-wave vacuum tube rectifier. This tube which is of the commercial type 5R4GY type is connected with the rectifier transformer T-3 to supply the required voltages to the tubes. It rectifies the alternating current of the proper stepup secondary voltage, which is applied through the transformer from the 440-volt, 3-phase, 60-cycle projectile hoist supply therefor. The tube output supplies the 600 volt direct current plate circuit for the amplifier.

35 The 300 volt direct current plate supply for the amplifier is supplied through vacuum tube V-12 which also is a full-wave vacuum type of the 5R4GY commercial variety. It is supplied through transformer T-4 which in turn has the primary thereof connected to the 440-volt, 3-phase, 60-cycle supply.

40 Similarly, vacuum tube V-13 is of the 5R4GY full-wave type and is connected to rectifier transformer T-5 from a similar power source. This tube supplies the 230 volt direct-current supply for the indexing drive control circuit.

45 In addition to the hereinabove recited transformers T-3, T-4, and T-5 the circuit includes transformer T-1 which serves as an interstage driver transformer and the transformer T-2 which is an output transformer.

The interstage transformer T-1 functions as a coupling 50 transformer for connection between the third and fourth stages of the amplifier; the primary thereof is energized by the push-pull third stage and induces a voltage in the secondary thereof to control the grids of the push-pull fourth power stage.

55 The primary of the output transformer T-2 is supplied by the push-pull fourth stage and functions to energize the control field of the regulating motor.

The transformer T-4 functions as a rectifier transformer operating through connections to the plates of 60 the vacuum tube rectifier V-12, to supply the necessary

potential to the plates and filaments of the vacuum tube rectifier. An additional secondary thereof supplies in a conventional manner the filament current for the vacuum tubes of the amplifier and the vacuum tube relays.

Rectifier step-up transformer T-3 has the primary side thereof connected to the 440-volt, 3-phase, 60-cycle supply. Its secondary windings are connected to the plates of the 600-volt vacuum tube rectifier V-11. A second secondary thereof is connected as shown in Fig. 10 of the schematic diagrams to the cathodes of the rectifier tube thereof in a manner to supply the necessary potential to the plates and cathodes of the vacuum tube rectifier.

Transformer T-5 similarly is a rectifier transformer adapted for connection to the same power source. One secondary thereof is connected to the plates of the 230-volt vacuum tube rectifier V-13. The second secondary connection is connected to the filamentary cathodes, of the same tube. The transformer thus functions to supply the necessary potential for rectification across the plates and cathodes of this vacuum tube rectifier.

The transformer T-6 is a safe signal transformer; the primary side of which is connected by two leads to one phase of the same power source as the hereinabove recited transformers. The secondary side thereof is connected to the safe terminals on the selector switch BW of the gun captain's control panel shown in Figs. 9 and 10. The transformer functions to impress a fixed voltage of approximately 90 volts, for example, as a "safe signal" on the stators of the three control transformers whenever the switch is turned to "safe" position. As the result of the action of this transformer a fixed voltage is induced in the rotors of the synchro control transformers causing the regulating motor to drive the output shaft and consequently the fuze setter, to set the projectile to "safe." Additionally the transformer energizes the primary of transformer T-8, the CT bias circuit, the field of regulating motor M-1, and the regulating safety circuit when switch BW is in "safe" position.

Transformer T-7 is the CT bias transformer, hereinbefore made of reference. The primary side thereof is connected through a resistance network and a condenser to the 115-volt synchro supply. The secondary thereof is connected to the rotor windings of the synchro control transformer CT-1. This transformer functions to supply a small constant alternating-current bias voltage to the control transformer of the required phase to prevent the possibility of false synchronization.

Transformer T-8 serves as the generator field supply transformer with the primary side thereof connected to the 115-volt synchro supply as is transformer T-7. The secondary thereof is connected to the generator field of the velocity generator G-1. This transformer functions to step-down the 115-volt synchro supply to 25-volts for the field supply of the velocity dampening generator 91.

Choke CH-1 is connected in series with condenser C-21 across the output of the 600-volt direct current rectifier tube V-11 as illustrated in the schematic diagram of Fig. 10. This choke, acting in conjunction with the condenser C-21, functions to filter the rectified alternating-current voltage and minimize ripple in the direct current supply to the amplifier.

Choke CH-2 is connected in series with the rectified 300-volt direct-current output in an inductance-input filter network incorporating filter condenser C-22 and C-23 which are connected across the rectifier output. This direct current rectifier filter arrangement is conventional and functions in a well-known manner to smooth out ripple occurring in the rectified voltage and thereby produce a more uniform direct-current output.

The potentiometer P-1 is a gain control potentiometer which is connected between the first and second stage of amplification to provide controlled increase or decrease in the sensitivity of the amplifier by manual adjustment thereof.

The potentiometer indicated at P-2 is a signal control potentiometer connected in the amplifier circuit in a manner to control the signal input voltage thereto. Similarly as P1, it is provided with a manual adjustment which facilitates voltage adjustments for increase or decrease of signal control. This control is such that with an increase in the signal control voltage the effect produced is that of reducing the velocity dampening voltage to decrease dampening action.

10 The condensers C-1 and C-2 of Fig. 10 are connected respectively in parallel with the relay coils of the vacuum tube relay systems RVY-1 and RVY-2. They function to filter the pulsating current flowing through the relay windings in a manner to produce a more uniform voltage 15 across the relays and prevent any possibility of contact chattering. Condenser C-3 is an element of the amplifier circuit wherein it is connected in the first stage of amplification thereof from ground to cathode of vacuum tube V-5. It serves as a shunt by-pass across the cathode resistor R-22 to shunt the alternating-current component 20 of the plate current of this vacuum tube so that variation in plate current will not effect the potential on the tube cathode. The condenser C-4, shown in the amplifier schematic, is connected between the plate of tube V-5 25 and ground wherein it by-passes high frequency signals to prevent high frequency oscillations in the circuit.

Condenser C-5, Fig. 7, is connected to ground the resistance-capacitance filter network between the first and second stages of amplification. It functions in conjunction with this network to produce a required phase shift 30 of the first stage output voltage as well as the function of filtering the third harmonic of the 60 cycle signal.

The screen grid by-pass condenser C-6, Fig. 7, is connected to the screen grid of tube V-5 of the amplifier circuit and in series with condenser C-3 in a manner to maintain equal potential between the cathode and the screen grid, and to prevent oscillations in the circuit.

The coupling condenser C-7 is connected between the output of tube V-5 and the input of the second stage at 40 tube V-6. It precedes the filter network and passes the alternating-current component or output of the first stage to the second stage, and additionally prevents the passing of direct current plate potential to the grid of the second stage.

45 The resistance-capacitance filter network includes the condensers C-8 and C-9 between the first and second stages of the amplifier. They function as a part of the phase shifting-filter network therefor.

The condenser C-10 which is connected between the plate and grid of one section of the dual triode vacuum tube V-6 in the second stage of amplification helps to produce a negative feedback, which while slightly reducing the gain of the second stage acts to suppress oscillation therein and reduce harmonics in its output. The 50 condenser C-11 of the amplifier circuit is connected between the plate of the hereinbefore described section of the dual triode V-6 with the connection thereof between the plate and ground in a manner to shunt high frequency harmonics from plate-to-ground.

60 The coupling condenser C-12 functions in a manner similar to coupling condenser C-7 to pass the amplified signal from the tube V-6 to the grid input of tube V-7, and to insulate the grid from direct-current potential. The output of the second section of the dual triode V-6 65 is coupled to condenser C-13, Fig. 7, similarly as the first section is coupled through condenser C-12 to the grid of the beam power tube V-8. The condensers C-14 and C-15 are connected in the primary circuit of the interstage transformer T-1 wherein they function to keep the amplifier stable by by-passing high frequencies from the transformer.

Condensers C-16 and C-17 in the primary of the output transformer T-2 are connected in parallel to the transformer primary and in series with each other in a 70 manner to match the reactance of the output impedance

so that the load thereon will approach unity power factor and result in a delivery of greater power to the regulating or follow-up motor. Filter condensers C-18 and C-19, Fig. 7, are connected in a series relationship from the 300-volt direct current supply of rectifier V-12 to the plate supplies of tubes V-5 and V-6 respectively. Their function is that of smoothing out the ripple of the rectifier output.

Condenser C-20 is connected in parallel with resistors R-39 and R39A in the CT bias circuit as shown in Fig. 10. This condenser-resistor network functions to provide the proper phase shift of the control transformers bias voltage from CT.

Condenser C-21 is connected in series with choke CH-1 in the choke input filter circuit for the 600-volt rectifier. Condensers C-22, C-23 with choke CH-2 are connected across the rectified 300-volt output of tube V-12 in an inductance input filter arrangement which functions to filter or smooth out the rectifier voltage and produce a more uniform output therefrom. Condenser C-27 is connected in series with resistor R-51 in the indexing drive control circuit across the contacts of indexing switch SW-5 in a manner to eliminate the arcing.

Condenser C-28 is connected across the output of the 230-volt rectifier as a condenser type filter. It is used in the circuit to reduce pulsation of the rectified direct current.

The circuit includes conventional resistors, designated by the prefix R. The designation series runs from R-1 to R-52 inclusive. With the addition in the series of resistors R-21A, R-39A, R-40A, R-43A, R-44A. The manner of connection of these resistors in the electrical circuit is hereinafter explained more fully in the description of the system's operation.

The resistors R-40, R-40A, R-41, and R-42 are connected in the CT bias circuit as shown in Fig. 10 to produce the proper voltage and phase shift in the circuit output of transformer T-7.

The resistors R-43 and R-43A are connected across the output supply of the 600-volt rectifier to function as a bleeder therefrom to prevent a charge being sustained by the condenser when the system is deenergized.

Resistor R-51 is connected in series with condenser C-27 in the indexing drive control circuit in a manner whereby the network functions to eliminate any tendency toward sporadic flow of current or arcing of the contacts of the indexing switch SW-5.

Resistors R-54 and R-54A are connected in parallel across the 230-volt direct current rectifier output to serve as bleeder resistors to dissipate any charge which might be sustained by condenser C-28 when the circuit is deenergized.

The relay units of the electrical system are designated by the prefix RY for the conventional relays and RVY for the vacuum tube relay systems. Relay RY-1 is a response selector relay which functions as an electrically operated switching device to control the CT error voltage during the engagement of the indexing drive. It is connected in the indexing drive circuit of the B-unit. It functions when deenergized in a manner whereby the relay switches thereof control the CT transformers in order that the error signal from CT-1 and CT-3 may be transmitted through the relay, while the signal from control transformer CT-2 is cut off at the relay. When energized, the relay-switches control the error signals from CT-1 and CT-3 back to CT-2 as described hereinafter in the operational description.

Relay RY-2 is an electrically controlled switching device which serves as the safety circuit interlock relay. It functions when energized to open the circuit and prevent release of a projectile during the indexing drive. Alternatively it operates until the fuse setter pawls have been positively engaged by three dead turn rotations. It is electrically connected in the indexing drive control circuit to operate in conjunction with other elements as described in the description of the system operation.

Relay RY-3 is an electrically controlled switching device which serves as a release circuit interlock relay to control release of the projectile. This relay is controlled by elements of RVY-1, RVY-2, RY-2 and the minimum fuse setting switch SW-4 of the regulator safety circuit. These other elements are connected in series with the coil thereof. The contacts of this relay are connected in the projectile release circuit in a manner whereby the relay coil must be energized, as one of the conditions to be met, before the projectile may be released from the fuse pot.

The relay RY-4 serves the system as a time delay relay. It is connected in the indexing drive control circuit in a manner to be controlled by the action of relay control switch BZ-2 at 158 for energization thereof. This relay 15 operates in conjunction with other elements of the indexing drive control circuit to control the action of the magnetic clutch and brake coils 171 and 173 respectively. When a projectile enters the fuse pot, relay RY-4 coil is deenergized although the circuit is maintained for a short 20 period of time through the time delay action of the short-circuited coil thereof. The relay is designed to provide approximately 0.4 second time delay in the switching action thereof.

The vacuum tube relay RVY-1 is a more accurate 25 switching device which provides snap action for a very definite and desired voltage value or condition. It is connected in the low-speed signal vacuum tube circuit in a manner whereby it serves as a speed transfer relay. It is controlled by the low speed error signal to function 30 in transferring control from the high-speed signal to the low-speed signal, and to open the regulator safety circuit whenever the low-speed signal is in control.

Vacuum tube relay RVY-2 serves as a synchronizing 35 relay, wherein it is connected in the high-speed signal vacuum tube relay circuit in a manner to be controlled by the high-speed signal. It functions to open the regulator safety circuit when the error voltage exceeds a predetermined value to prevent release of the projectile until such time as its fuse is properly set. This relay 40 thus functions to indicate synchronism and to permit release of the projectile. The operation of this relay is essentially identical to that of relay RY-1, the only difference being in the voltage sensitivity for operation thereof. The particular function of the vacuum tube relays with respect to the circuit relays is more fully 45 described in the following description of the mode of operation of the system thereof.

The electrical switches of the system comprise seven 50 units. This includes the switches BZ-1 and BZ-2 associated with the fuse pot in a manner to be placed in an operating condition as a projectile enters the fuse pot. The fuse pot movement with projectile reception is such that starting switch BZ-1 and relay control switch BZ-2 are actuated immediately and simultaneously by the translatory movement of the retract shaft which is connected 55 to the fuse pot housing.

The master control of the system is facilitated by a 60 switch on the gun captain's control panel designated BW. It is a multiple three position manually operated switch having "off," "run" and "safe" positions thereon. The system additionally comprises switches SW-4, SW-5, SW-6 and BBR-3. Switch BBR-3 is a relay operated switch connected in the 440-volt, 3-phase, 60-cycle supply. The relay coil winding of this switch is made active 65 whenever the switch BW is turned to either the "run" or "safe" position. It functions to activate the 440-volt circuit to the safe signal transformer for application of a safe control voltage on the control transformers and hence on the regulating motor. Regulating motor operation provides rotation of the fuse to a safe position thereof. Energization of this relay switch BBR-3 coil is by the 115-volt, single-phase, 60-cycle supply. Additionally it closes the circuit to the transformers of the rectifiers 70 for the 300-volt, 600-volt and 230-volt direct current sup-

plies, the blower motor M-3 and the indexing motor M-2.

Minimum fuse setting switch SW-4 maintains a minimum fuse value on the control transformers at all times. It is associated with the output drive through cam CA-2, as shown in Fig. 9.

The indexing switch SW-5 of the system at 114 is operated by the indexing cam CA-1 at 111 with the switch rollers 174 thereof in alignment with the contour surfaces of the cam for actuation therefrom. The brake auxiliary cam switch SW-6 at 113 is operated by the brake cam CA-1a at 112 in a manner similar to that of SW-5. The combined actions of switch SW-5 and switch SW-6 control the indexing drive cycle by regulating the action of the magnetic clutch CM-1 at 171 and magnetic brake BM-1 at 173.

The locked-in synchronization between the fuze pot drive and the receiver-regulator output 74, whereby the setting dog position is correlated with the fuze signal is provided by the adjustable input coupling 24. It is arranged to positively connect the fuze pot-setter input shaft with the receiver-regulator output shaft. A vernier coupling worm at 165 is arranged in meshing engagement with the gear sleeve 175 provided in the coupling hub whereby fine adjustments may be made to synchronize the fuze setter with the receiver-regulator.

Referring now to Fig. 10 of the drawing the input supplies, and the connections of the fuze setter electrical system with the electrical system for other elements of the turret, are shown to include the lines PS-1 and PS-2 which are connections for the gun control system and function in conjunction with the projectile pawl trip circuit solenoid thereof. A 115 volt synchro supply input is indicated by the reference characters SY-1 and SY-2 as they feed into the input cable. Corresponding reference is made thereto at the terminal connections to the master switch BW. The coarse signal input or 1-speed signal is shown as CS as it leads into the cable and corresponding connections therefrom to the switch are similarly shown, as is the case with the fine signal control or 18-speed input indicated by the reference character FS. The 115 volt single phase 60 cycle A. C. supply which may be derived, for example, from the projectile hoist supply is shown as including the leads PS-1 and PS-2. The 3 phase, 440 volt, 60 cycle A. C. supply is shown with the respective leads thereto indicated ϕ -A, ϕ -B, and ϕ -C at the separate phase terminals therefor. The three lines are suitably fused prior to control thereof by relay switch BBR-3 which swings three contactors across the respective terminals thereof, and prior to the showing of the entrance of these leads into the 3 phase cable. The motor units M-2, and M-3 which are Y connected as 3 phase devices thereacross are respectively connected in parallel. This supply source also provides single phase taps for the power transformers T-3, T-4, and T-5 as well as for the safe signal transformer T-6. The respective phase connections for these transformers are shown for T-3 as being across ϕ -B and ϕ -C, that for transformer T-4 being ϕ -A and ϕ -B. The connections for transformers T-5 and T-6 are in parallel across the single phase terminals ϕ -A and ϕ -C as shown.

The four secondary taps from transformer T-6 are shown respectively as SS-1, SS-2, SS-3 and SS-4 and are provided for the application of their respective safe signal voltages across the control transformer when the switch BW is turned to the "safe" position.

The coarse signal input is indicated as CS as it provides for flow to the several switch elements. The flow across the switch terminals through respective contactors thereof to the control transformer primaries is designated by the prefix CP for the primary inputs respectively CP-1, CP-2, and CP-3. The fine signal input FS for application to the fine control transformer CT-3, when passed across the switch terminals is changed in designation to read FP for the fine primary connections. The coarse

control output from the control transformers CT-1 and CT-2 is shown for the secondary of control transformer CT-1 to include the secondary leads CC-1 and CC-2 which are connected therefrom to terminal connections 6 of RY-1 and T-7 respectively. The secondary lead CC-3 of control transformer CT-2 is connected to a second terminal of RY-1. The fine control output indicated across FC-1 and FC-2 is derived from the fine control signal FS as applied through the control transformer 10 CT-3 from fine primary connections FP. The lead FC-1 thereof is connected to one terminal of the potentiometer P-2 and to the resistor R-11 of the vacuum tube relay grid signal input for tube V-3. The second lead from the fine control transformer secondary indicated 15 FC-2 is connected to ground.

The connections from the three control transformers, the hereinbefore mentioned 3-phase input, and the power supply input are shown for purposes of clarity of illustration as being enclosed in cables. Also the output across 20 the output transformer T-2 of the amplifier is applied through a cable wherein the connections AM-1 and AM-2 as amplified outputs are applied respectively across the control winding of the motor M-1.

The circuitry of switch BW includes an auxiliary circuit 25 for projectile pawl release control. It includes the terminals GS-1 and GS-2 which are controlled in normal fuze setting operation by action of relay RY-3. The cable for connection between terminals of switch BW and relay RY-3 additionally includes connections PS-1 and PS-3 which provide current flow through signal lamps L when relay RY-3 is actuated. The power source for this lamp operation is derived from the 115 volt, single phase, input across PS-1 and PS-2. The light signal functions in a manner as is apparent from Fig. 8, to indicate the completion of the fuze setting operation. As RY-3 actuates the contactors to close these circuits across the terminals thereof, the projectile pawl trip circuit solenoid referenced (SAG) in Fig. 8, but not shown, is actuated to provide for projectile release and ejection 40 thereof from the projectile cradle 12 by action of the ram spring 23. See copending application to P. H. Girouard et al., Serial No. 153,262.

The functioning of switch BW in this circuit provides for bypass of the fuze setting system when it is desired to use projectiles of a non-fuze set variety. The control by switch BW is that of closing the circuit for solenoid SAG through the terminals GS-1 and GS-2 thereof when the switch is turned to the "off" position thereof. The closing of the circuit through GS-1 and GS-2 is accomplished by the relay RY-3 when switch BW is at either "run" or "safe," and then only when the fuze has been set or rendered safe by the fuze system.

The several direct current supplies for the system as provided by the rectified outputs of the 600 volt, 300 volt and 230 volt power transformers T-3, T-4 and T-5 supply D. C. voltages thereto indicated respectively B-1, B-2 and B-3 on the drawings. The additional direct current connections of the circuit which are shown on Fig. 10 as B-4 through B-8 inclusive are derived from the 230 volt rectified source. These B voltages are applied to the relay coil windings, the magnetic clutch coil and the magnetic brake coil for direct current operation thereof. The designations B-4 to B-8 are provided for the lines thereof to permit identification of terminal connections and to permit differentiation thereof with respect to alternating current lines, synchro supply, and control transformer connections of the system.

Operation of fuze setting control system

The fuze setting mechanism is placed in operation upon reception of a fused projectile in the cradle, as fed thereto by the hoist system of the turret.

Let it be assumed for the purpose of description that the fuze pot is engaged and the retract handle is in a position permitting engagement of the switches BZ-1

and BZ-2 associated therewith to activate the controls of the receiver-regulator drive unit therefor.

Projectile fuze setting operations take place and are completed in the projectile cradle. The projectile nose is initially received in the holding and setting cup assembly of the fuze pot as the projectile is moved upwardly into the guide 13, of the projectile cradle assembly 2. The ram spring 23 encased by the fuze pot housing is compressed by action of the conveyer hoist flight to provide for release of the projectile during its ramming phase at the gun transfer trays. The fuzed projectile 12 is engaged by the fuze pot 5 and maintained in contact with the cup members by action of the projectile retaining pawl, not shown, of the cradle. The action of this projectile retaining pawl of the cradle is controlled by the solenoid designated SAG in Fig. 8 which is in the projectile pawl trip circuit of lines GS-1 and GS-2 of Fig. 10. The function of this solenoid control will be apparent and more fully understood from the description of the operation of the system which follows.

The drive assembly, for the holding dog 14 and the setting dog 16 which are mounted in their respective holding and setting cups, is enclosed within the cradle housing as hereinbefore described in greater detail. The gearing of this drive includes a differential gear unit arranged in a manner whereby the pawls or dogs travel in mutually opposed relationship with each other upon rotation of the single input at 24. The arrangement is such that the pawls will approach each other with one direction of rotational input and separate with rotation in the opposite direction. This arrangement satisfies the condition necessary for proper representation of fuze setting angle when the device is synchronized, in accordance with control input, with the receiver regulator and the particular orientation of the pawls taken as a pair has no significance since the insertion of the projectile into the guide and fuze pot assembly is a random orientation whereby the fuze slots in the nose thereof differ positionally with each projectile insertion. However once the hereinbefore described three-turn orientation including two dead turns, is complete, the position of the slots represented by angular separation therebetween or between the pawls of the fuze setter represent fuze setting angle when the device is in synchronization or in approximate fuze angle relationship until synchronization is complete. After initial synchronization with the fuze setting order, the relationship of the pawls is such as to advantageously change fuze setting order in the fuze with change of fuze setting order input from the plotting room of the ship, it thus functions to reestablish the correct synchronization relationship between the incoming signal and the fuze angle at all times thereafter. This provides the advantage that the fuze may be set and thereafter have the setting altered or the fuze set to "safe" by control at switch BW while the projectile is in the cradle.

The indexing motor M-2 operates continuously although the drive output thereof is applied to the differential 116 only when the fuze holding cup is under rotation to provide engagement of the fuze holding dog with the corresponding fuze slot. The application of drive energy is through the clutch-brake combination which operates when electrically energized to release the clutch disc 99 from the braking surface 172. Simultaneously with this release action of the clutch disc 99, it is pressed against the rapidly rotating clutch surface of the motor flywheel 98. This transfer is made magnetically by D. C. coil BM-1 of the brake solenoid winding 173. The cooperative action of this brake and clutch assembly is such as to provide a rigid brake action when the output is not operative and to provide a rapid energy transfer when the gearing is required to run. With the continuously operative motor there is no speed loss due to motor pickup, and the energy transfer is accomplished with satisfactory rapidity.

The drive assembly for the holding dog and the setting dog is placed in operation by positioning switch BW at

the "run" position thereof for dog rotation to a position in engagement with a mating portion of the projectile nose. As hereinabove described, setting dog engagement with the rotatable fuze parts follows after holding dog engagement. Also the setting cup is arranged to receive sufficient rotation after holding dog engagement to prevent false synchronization at a 180 degree out of phase condition.

The drive input to the fuze pot gear mechanism is applied at the coupling 24 between the receiver-regulator A-unit and the cradle proper. This input imparted from shaft 74, and hub 25 to the coupling hub 26 drives through a gear train 27, 30, 32, and 41 hereinbefore described in greater detail to drive the external ring gear 42 of the lower differential gear assembly at the holding cup. This differential assembly rotates the holding cup bevel gear 45. The ring gear 42 additionally rotates the bevel spiders 43, and 44, and the upper bevel gear surface 46 of the double intermediate gear 53 located in parallelism with the holding cup gear 45 to apply rotational motion through the second bevel surface of 53 to the fixed bevel idler gears 48 and 49 of the upper differential to the extreme upper bevel gear 54 which imparts the drive energy through drive 56 and shaft 57 for setting dog rotation. The showing of Fig. 3 clearly illustrates the driving arrangement when taken in consideration with the detailed description of the specific elements of the receiver-regulator drive.

The driving power for the fuze pot assembly of Figs. 2 and 3 is provided by an output or mechanical response from the receiver-regulator, or A-unit, of Fig. 5. This receiver-regulator drive is shown schematically in Fig. 1, and diagrammatically in Fig. 6.

The cooperative and interassembly relationships as to function and mode of operation of the fuze setter mechanical and electrical units are presented in diagrammatic form in Fig. 9, to facilitate a better understanding of the primary and auxiliary control actions thereof.

The power or electrical function relationships are represented by bold flow lines with arrow indications as to direction of application. The electrical auxiliary control or power functions are represented in a similar manner by broken lines of flow. The mechanical function applications are shown in outlined bold flow lines, with secondary or auxiliary mechanical functions shown in broken outline.

The control for setting the fuze nose to a particular fuzing value is applied to the system as a fuze setting order from either the forward or aft plotting rooms as indicated in Figs. 1 and 9. This signal is applied through a switch of Fig. 9 in the turret officer's transfer switch board, from which it is transmitted to the gun captain's control panel through the switch BW shown in greater detail in Fig. 8. This input to the switch BW is in the nature of a connection FS for the 18-speed and the connection CS for the 1-speed inputs as well as connections SY-1 and SY-2 for the 115-volt synchro-supply from the turret officer's transfer switchboard applied through switch BW as hereinbefore described in greater detail with reference to the electrical schematic showing of Fig. 10. The coarse signal input CS from switch BW to the control transformer CT-1 of Fig. 10 is applied mechanically as shown in Fig. 6 to drive the dial DL-1 of Fig. 9. Similarly this signal CS is applied to the control transformer CT-2 whereby it produces an error voltage across CC-3 and ground which is applied through similarly designated terminal connections of the relay switch RY-1 when closed to apply this voltage in opposition to the voltage on the stator windings of the generator G-1 for damping operation prior to application of the error signal to the amplifier.

The 18-speed circuit FS from the switch BW at its "run" position is applied as shown in Fig. 8 to control transformer CT-3, the output of which is applied through FC-1 and FC-2 to the electronic relays RVY-1 and

RYV-2.

The 115-volt synchro supply across SY-1, SY-2 from the turret officer's transfer switchboard is applied through switch BW to the primary of transformer T-8 for the damping generator G-1 and to the stator winding of the regulating motor M-1, the rotor of which mechanically operates the output or response drive for the holding cup assembly. The 440-volt 3-phase, 60-cycle supply designated ϕA , ϕB , ϕC from the projectile hoist source has the three separate single phases thereof applied to the primary of transformer T-6, to the transformers of the 230-volt rectifier, the 300-volt rectifier and the 600-volt rectifier. It is connected in 3-phase relationship to the stator of blower motor M-3. This supply additionally drives the 3-phase indexing motor M-2. The control of indexing motor M-2 is governed mechanically in clutching and braking operation by clutch CM-1 and brake coil BM-1.

Transformer T-6 as will be recalled from the foregoing description thereof applies a safe signal for the control transformers through the switch BW and substitutes this signal for the 1-speed and 18-speed control inputs CS and FS respectively when this switch is positioned at "safe." The 300-volt and 600-volt rectified currents are applied as the B supplies to the amplifier or B-unit which in turn has its output across AM-1 and AM-2 applied to this regulating motor M-1 to control the operation thereof. This control is tied in with the velocity damping generator G-1 which opposes the signal input to the amplifier. The 230-volt rectified current supply is applied through the switches SW-5 and switch SW-6 when activated by the cam surfaces CA-1 and CA-1a. The circuit for this direct current supply when closed through these cam switches is applied to the clutch coil CM-1 to permit driving operation by indexing motor M-2 for indexing the holding and setting dogs three relative rotations.

The mechanical drive arrangement of the system is believed to be obvious in view of the hereinbefore described driving relationship of the several gear elements to drive the output or response shaft which is connected through the input coupling 24 to the gear 27. Likewise it is believed obvious that by tracing the gear train relationships of Fig. 6 from the motor 95 to the differential 116, the drive of the indexing motor to the above recited shaft 74 also follows.

The control transformers and the velocity damping generator are mechanically synchronized with the rotor of the regulating motor M-1 for driven rotation therefrom. It is this rotation of the transformer rotors which causes the error signal voltage to be induced therein with respect to the fine and coarse control signals applied on the stators thereof. When they have been rotated into synchronism with this input signal no voltage is introduced into the rotor windings and the control voltages cease being applied to the amplifier.

The fuse setting receiver-regulator which is placed in operation upon the reception of an electrical fuse setting order by the synchro-supply transmitted to the stators of its control transformers induces this error voltage in the rotor of the control transformer whenever the position of the rotor is not in correspondence with the positional signal transmitted to the regulator. This error voltage is amplified and raised in power level to control the operation of the follow-up or regulating motor M-1. This is necessary inasmuch as the incoming fuze time-setting synchro-signal is too weak to control operation of the fuze setting mechanism. These synchro-control transformers function to originate the error voltages which as above stated control the regulating drive through coarse and fine control of the equipment. The amplifier is provided to step up the power level of the synchro-control transformer error voltages to a degree sufficient to control the regulating motor M-1 at 75 of Fig. 6. The regulating-motor response drives the output shaft of the regulator and is connected to the fuze setter input. The response also positions the rotors of the control trans-

formers in a direction to reduce the error voltage to 0. It will be apparent that whenever an angular displacement exists between the incoming fuze setting synchro-signal and the position of the output response, the amplifier error voltage will cause the regulating motor to drive the system into synchronization. This regulating motor thus functions to rotate the setting and holding cups to an angular displacement with respect to one another which is in proper synchronism with the incoming fuze time-setting synchro signal. This action takes place whenever the selector switch BW is turned to "run" or "safe" position and a signal is impressed on the equipment.

The angular displacement between the setting cup and the holding cup is maintained and is in synchronism with the incoming signal, regardless of whether or not a projectile is present in the fuze pot.

The velocity damping generator G-1 is driven by the mechanical response and introduces a voltage to the amplifier which is proportional to the velocity of response and functions to oppose the error voltage. This dampening voltage eliminates oscillation and facilitates smooth action response of the system to the input signal.

The operation of the vacuum tube relays Figs. 8 and 10, of the system are essentially identical; the only difference being in the voltage sensitivity at which the units operate. The relay RVY-1 is controlled through action of control transformer CT-1 by the low or 1-speed error signal FS and is used to transfer control between low-speed and high-speed signals. Additionally it opens the regulator safety circuit whenever the low-speed signal is in control of the system. The vacuum tube relay RVY-2 is controlled in a similar manner by the high speed signal CS as applied through control transformer CT-3 to open the regulator safety circuit when the error voltage exceeds a predetermined value.

When there is no signal input, resistors R-3, R-4, R-5 and R-6 across the 300-volt direct-current supply act as voltage dividers to supply the proper bias voltages to the cathode, suppressor grid, and screen grid of the pentode tube V-1. The control grid is at ground potential and is therefore negative with respect to the cathode, which has a small positive voltage. Plate current flowing in R-7 drops the operating voltage to a very low value which voltage is applied to the grids of the tube V-2. This tube is connected in a manner to act as two triodes operating in parallel and the cathode of this tube is biased by means of the voltage divider comprising resistors R-8, R-9 and R-10 wherein direct current from the 300-volt rectified source is applied to the plate through the relay coil of speed transfer relay RVY-1. The bias of the cathodes is higher than the voltage applied to the control grids, whereby the grids are effectively biased negatively in a manner to limit the plate current to a value insufficient to energize the relay coils. The relay is thus de-energized for the condition of a zero signal value.

The action of the circuit when the input signal reaches a value at which the relay should be energized depends upon the operating characteristics of the tube V-1 which as hereinbefore stated may be of the type commercially designated as a 6SJ7. The tube circuit is such that only relatively large negative grid voltages will produce plate current changes. Small signal input voltages are ineffective with respect to the operation of the circuit. With a sufficiently large signal input the circuit functions to provide switch contact changes in response to operation of the relay coil thereby. The positive half cycle of the signal input and a portion of the negative half cycle cause no change in the plate current of the tube V-1. At the low point of the negative half cycle, however, the control grid thereof is made sufficiently negative to cause a reduction in plate current. In this portion of the cycle wherein the plate current decreases, the voltage drop in resistor R-7 decreases accordingly and the plate voltage increases. The pulses in the plate voltage applied to the grids of the tube V-2 causes corre-

sponding pulses in plate current. Condenser C-1 is discharged during each pulse. The condenser then discharges through the coil until the next pulse appears. The result is a pulsating direct current flowing in the coil, of sufficient value to energize the relay continuously as long as the signal input of required strength is received.

The vacuum tube relay RVY-1 is controlled by the output voltage of the 1-speed control transformer. When this voltage is for example 4.5 volts or greater regardless of the direction of displacement, the relay is energized and the 1-speed signal controls the follow-up. When it drops below 4.5 volts the relay is de-energized, switching control of follow-up, but not of the relay, to the high speed signal.

It is apparent that if the system is displaced to the 90° point from synchronization and then energized, the 1-speed signal will take control, driving the follow-up toward zero. When the displacement has been reduced to a small amount, the 1-speed signal will become less than 4.5 volts, whereupon the high-speed signal will be switched into control. This causes a much larger error voltage to be produced, the consequence of which is the driving of the system into closer synchronism than would be attained under 1-speed control.

Let it be assumed for purposes of description that the system is displaced close to 180° from synchronism at the time of energization, a false synchronism 180° out of phase results therefrom. The output of the 1-speed control transformer is then less than 4.5 volts, resulting in a de-energized condition of the vacuum tube relay whereby the high-speed signal takes control thereof, driving the follow-up into 180° displacement position and keeping it there. To prevent the possibility of this false synchronism, the system is altered slightly in a manner whereby the rotational position of the 1-speed control transformer is shifted slightly. A small constant alternating current bias voltage is added by the control transformer bias circuit of Fig. 8, to the shifted 1-speed signal, producing a new effective 1-speed signal.

Under these conditions of operation, the 1-speed signal will be controlled at the 180° displacement point, to drive the system to the right through 270° to a point approaching 0°, where the high-speed signal will be switched in for fine control. Through a small range near 165°, the high-speed signal will be in control momentarily but it will simply drive the system toward 180° until the 1-speed signal again takes control. The high speed signal is effective in synchronizing the system only at the proper point of control. The possibility of false synchronizing is thereby eliminated.

The amplifier as shown by the schematic diagram of Fig. 10, is provided in the system since the voltage and power level of the synchro control transformers' error voltages are insufficient to control the regulating motor M-1. In order to utilize the error voltages of these synchro control transformers, a 4-stage, high gain power amplifier is employed in the control circuit to supply the desired voltage and power level to control the regulating motor.

The first stage of amplification employs the pentode-type vacuum tube designated D-5, to operate as a class A voltage amplifier. The damped error voltage from generator G-1 is applied thereto through resistor R-21 at the control grid. This resistor limits the flow of grid current when the signal level becomes too high. Plate potential for this tube is obtained from the 300-volt rectifier and dropped to the required voltage by resistor R-24, which varies the plate potential with variations in plate current. The voltage at the plate at any instant equals the supply voltage minus the drop due to plate current flowing in the resistor R-24. Decoupling of the plate from the preceding stage is accomplished by resistance R-29 which with condenser C-18 provide a resistance-capacitance filter for the direct current plate supply.

In class A operation, plate current flows at all times.

The plate current circuit is from the 300-volt rectifier through resistor R-24 to the plate, through the vacuum tube to the cathode, and through resistor R-22 to ground. Alternating voltage signals, applied to the control grid, cause the plate current to vary so that, in effect, an alternating plate current is superimposed on the normal plate current. This action causes corresponding variations of voltage at the plate of the vacuum tube. Condenser C-7 passes this alternating current component on to the second stage, while preventing the passing of direct current plate potential to the grid of the second stage.

The voltage drop, caused by normal plate current flow in resistor R-22, raises the cathode potential to the required value above ground, to thereby give the control grid, which is at ground potential, negative bias with respect to the cathode. Condenser C-3 shunts the alternating-current component of the plate current in a manner whereby variations in plate current will not affect the cathode bias potential. The screen grid supply is through resistor R-25, wherein a normal screen current flowing therethrough drops the screen voltage to the rated value.

The resistor R-23 is connected in series with the heater to reduce heater current and thereby reduce the tendency of the heater to emit electrons. This functions to reduce the gain of the amplifier slightly but produces the stability required in the early stages of high-gain amplifiers of this type. The condenser C-4 which is connected between the plate and ground by-passes all high frequency signals to prevent high-frequency oscillation in the circuit. The screen grid to cathode by-pass condenser C-6 affords a path for the alternating current component, to thereby eliminate any variation of the screen grid to cathode potential. A fixed potential of the screen grid with respect to the cathode is thus maintained thereby. The resistor R-21A, which connects the control grid of the vacuum tube V-5 to ground, acts as a grid leak to permit dissipation thereby of any charge occurring on the control grid such as may be caused by electron accumulation thereon.

The hereinbefore described phase-shifting-filter network which consists of resistors R-26, R-27, and R-28, and condensers C-5, C-8, and C-9 is incorporated between the first and second stages of amplification. This network functions to compensate for the shift in phase of the signal voltage throughout the entire signal system in a manner whereby the total phase shift between the input voltage and the output voltage of the amplifier lags by approximately 100°. Since the control transformer has a leading phase shift of 10°, the ultimate output voltage or control voltage to the regulating motor will be 90° out of phase with the applied main voltage. This is the phase-relationship condition required for the 2-phase operation of the motor M-1. The filter network which is inserted between the first and second stages also functions to reduce the third harmonic of the 60-cycle signal and prevent saturation of the power stages of tubes V-7, V-8, V-9 and V-10.

The second stage of amplification employs a twin triode vacuum tube designated V-6, which functions in this circuit as a class A voltage amplifier and as a phase inverter to drive the push-pull stage of amplification which follows. It operates as two independent triodes enclosed in the same envelope, which for purposes of clarity in the description of the circuit function thereof, are designated as the A section and B section.

The plates of tube V-6 are energized from the 300-volt rectifier, as applied through plate resistors R-31 and R-32. Cathode bias is obtained from the voltage drop across resistor R-30 in a manner similar to that hereinabove described as being employed in the first stage of amplification. Resistor R-36 and condenser C-19 function to filter the direct current supply. A portion of the potentiometer P-1 of Fig. 10 is connected between the control grid of section A and ground to act as a grid

leak therefor. This grid leak provides a direct current path between the tube grid and ground to thereby prevent the accumulation of a static charge on the grid.

The signal from the phase shift network is transmitted through potentiometer P-1 before being applied to the vacuum tube V-6. The amplifier error voltage from the first stage is applied across potentiometer P-1. Adjustment of the potentiometer arm regulates the value or portion of the amplifier signal which is to be applied to the section A control grid of the tube V-6 thereby controlling the overall gain of the amplifier. Potentiometer P-1 is adjustable to give optimum amplifier gain for good follow-up performance, and is then locked in position.

The signal, applied to the grid section A of vacuum tube V-6, is amplified in a manner similar to that described under the first stage. Resistor R-31 acts as a plate load resistor in this case. The amplified signal is passed through coupling condenser C-12 to the grid of vacuum tube V-7. Two output signals, equal in magnitude but of opposite polarity are desired from the signal stage. This condition occurs if the signal to the grid in section B of vacuum tube V-6 is equal and opposite in phase to the signal to the grid in section A of vacuum V-6. The method used to obtain this condition is hereinafter explained in greater detail.

The plate voltage, of this type of amplifier, is always opposite in phase from the grid signal. At an instant when the grid is positive, greater current flows and the voltage drop in the plate load resistor R-31 increases in an action which causes a decrease in plate potential such that in effect, the instantaneous alternating-current polarity is negative.

The output voltage of section A of the vacuum tube V-6, which is out of phase with the grid signal, is applied to vacuum tube V-7, across the grid leak resistor thereof. This grid leak comprises the series connected resistors R-33 and R-35. The alternating current voltage at the series junction between these resistors is applied to the grid of section B of vacuum tube V-6. This voltage is amplified in section B of the tube in a manner similar to that of section A with the output at the plate thereof being in out-of-phase relationship with that of section A. The output voltage of section B is passed through coupling condenser C-13 to the grid of vacuum tube V-8 and appears across grid leak resistors R-34 and R-35.

The two output voltages differ in magnitude, and this difference is a small amount of the total output voltage. This small difference in these two output voltages is the voltage applied to the grid, or is the grid signals to section B of vacuum tube V-6. The output of the second stage is, therefore two signals opposite in phase and nearly equal in magnitude.

Condensers C-10 and C-11 are used to improve the performance of the second stage. A portion of the plate output is passed through condenser C-10 to produce an overall reduction of the grid signal. This action, called inverse feedback, slightly reduces the gain of this stage; but acts to suppress oscillation and reduce harmonics in the output. Condenser C-11 shunts high frequency harmonics from the plate to ground.

The third stage of amplification employs two beam power-type vacuum tubes designated V-7 and V-8. These tubes operate in combination as class AB₁ push-pull amplifiers whereby they function to feed or supply the fourth or final stage of amplification. The plates of these two tubes are supplied from the 300-volt rectifier, the circuits for which are through the two halves of the divided primary winding of the interstage transformer T-1. The two tubes receive the oppositely polarized signal voltages, on the control grids thereof and produce plate current variations in accordance with signal changes. Since the signal voltages as applied thereto from the preceding stage are of opposite phase one of these two tubes conducts maximum current while the other is conducting minimum current. The drop in voltage of the

alternating current, as applied to each half of the primary winding of transformer T-1 differs in sign with respect to that of the other half thereof and produces an additive effect upon the alternating-current voltage across the entire primary. The total voltage effect thus provided is double the output of a single vacuum tube.

The cathodes of tubes V-7 and V-8 are biased by plate current flowing in the resistor R-38. The screen grid is supplied through resistor R-52 and normal screen grid current in this resistor drops the screen voltage to the rated value. Inverse feedback to the cathode is supplied from the amplifier output in order to reduce distortion and suppress oscillation. Inverse feedback is supplied to the push-pull stage by the third coil winding of the amplifier output transformer T-2. This negative feedback produces cathode potential changes which vary in phase with the grid signal and swings therewith to partially nullifying this signal and stabilize the linearity characteristics of the output from this stage through the succeeding stage to the amplifier output transformer. The center tapped interstage transformer T-1 couples the third stage at the divided primary thereof to the final push-pull stage. The value of loading resistor R-37 is selected such as to secure optimum loading on the third stage. The third stage is designed to saturate at the maximum allowable input voltage to the final stage. This relationship is such that an increase in input causes no change in output. The by-pass condensers C-14 and C-15 which are connected across the center tapped primary of an interstage transformer T-1 function to stabilize the amplifier by by-passing high frequencies from the transformer.

The fourth stage of amplification employs two triode power tubes designated as V-9 and V-10 respectively connected in push-pull relationship to operate at a high power level. The operation at this stage is identical to that employed for the push-pull beam power tube third stage, with the exception that no feedback is employed therein, and that a potential of 600 volts is applied between the plate and cathode.

Signal voltages from the secondary of the interstage transformer T-1, which are opposite in phase, or polarity, are applied to the grids of these two vacuum tubes. Plate currents thereof vary in accordance with these applied signal voltages. Since the signal voltages are of opposite phase one tube will be conducting maximum current when the other tube is conducting minimum current. The plate supply for vacuum tubes V-9 and V-10 is from the 600 volt rectifier as applied through the two halves of the divided primary of the amplifier output transformer T-2.

The alternating-current component of the plate current in vacuum tubes V-9 and V-10 produces out of phase alternating-current voltage drops in the two halves of the primary winding of a T-2 which are additive to produce the effect of an alternating-current voltage across the entire primary, which is double the output value of a single tube. The grids of the two tubes of this stage are biased at ground potential.

The output voltage of the amplifier as applied across the output transformer primary produces in the secondary thereof the control field supply for the regulating motor M-1. The resultant amplified controlling voltage as impressed on the control field is approximately 90 degrees out of phase with the synchro supply which energizes the main field windings of the regulating motor. These two applied voltages of 90 degrees out of phase relationship meet the requirements for 2 phase operation of this motor.

The condensers C-16 and C-17 as incorporated across the primary windings of transformer T-1 function to match the reactive component of the load in a manner to more nearly approach unity power factor for the motor M-1.

The amplifier output at transformer T-2 controls the operation of the regulating motor by controlling one of

the two phase windings, thereof, the follow-up of which mechanically rotates the control transformer rotors in a direction to reduce the error voltage produced therein. When the error voltage is reduced to zero, the response has been brought into synchronism and stops. With continuous reception of a constantly changing CT-setting the response continues to follow up so that correspondence is maintained between the positional signal received and the mechanical position of the regulating output drive.

The indexing motor which is connected with the mechanical drive through differential D-1 operates continuously, while the indexing drive associated therewith is maintained stationary by action of magnetic clutch CM-1. This clutch is disengaged by action of the magnetic brake BM-1 which is in turn engaged when no projectile is in the fuse pot. The response from the regulating motor M-1 is transmitted unaltered to the differential D-1 at 116 to drive the rotors of the control transformers CT-1 and CT-3, the check dials DL-1 and DL-2, the minimum fuse setting cam CA-2 and the setting and holding cups of the projectile cradle. The rotor of generator G-1 and control transformer CT-2 are also driven by the mechanical drive response by direct drive arrangements therewith.

It will thus be apparent that all of these elements are kept in synchronism with the incoming fuse time-setting signal as applied through the amplifier output to the control winding of regulating motor M-1.

The indexing drive circuit associated with motor M-2 is actuated immediately after the projectile enters the fuse pot when a circuit including switches BZ-1 and BZ-2 is actuated thereby. At this instant the brake BM-1 is released and the clutch CM-1 engaged to connect the indexing motor to the indexing drive. The control of the regulating motor is shifted by relay RY-1 from synchro control transformers CT-1 and CT-3 to control transformer CT-2. The latter transformer is driven directly by the regulating drive. The output drive is turned by the sum of rotations of the regulating and indexing drives added in the differential D-1. The indexing drive ensures that the fuse nose holding and setting dogs of their respective cups are engaged in the slots in the projectile fuze before the indexing drive has made the equivalent of three dead turns.

When this action has been completed, the indexing cam CA-1 operates the indexing switch SW-5 to disengage the magnetic clutch CM-1 and engage the magnetic brake BM-1 to stop the indexing drive. Control of the regulating motor M-1 is shifted back to synchro control transformers CT-1 and CT-3. The fuse setter is then brought into synchronism with the incoming synchro signal by the mechanical follow up which maintains such synchronization regardless of any change in the fuse time synchro signal. When this drive has become synchronized in the incoming signal a relay contact not a part of this invention but, in the cradle pawl tripping cylinder control circuit is closed to allow the projectile to be ejected from the cradle in a manner as described in the hereinbefore recited copending application to Girrouard et al. The relay functions of the system are such that with no projectile in the fuse pot the error voltages from the control transformers CT-1 and CT-3 are transmitted through the response selector relay RY-1 and the speed transfer relays RVY-1 and RVY-2, while the error signal from CT-2 is cut off at the relay RY-1. The magnitude of the 1-speed error voltage controls relay RVY-1 in a manner to connect the 1-speed error circuit to the amplifier when response is far from synchronization to provide course control thereover. When the response has driven the rotor of the course control CT to within approximately 5 degrees of synchronism, the speed transfer relay RVY-1 cuts off the 1-speed error voltage and relay RVY-2 connects the 18-speed control to substitute the voltage

from transformer CT-3 in place of the 1-speed error voltage for fine control thereover.

The circuit relationships for the application of the safe signal on the system is such that when the selector switch BW on the gun captain's control panel is turned to the "safe" position, the fine and coarse fuse setting orders, and the 115-volt synchro supply are cut off at the switch, for substitution through an alternative set of contacts of the fixed voltages from the safe signal transformer T-6.

10 The primary of the safe signal transformer T-6 remains energized by the 440-volt, 3-phases, 60-cycle supply. The voltage across the secondary terminals of the transformer T-6 energizes the regulator safety circuit, the generator field transformer T-8, the CT bias circuit, the main field of the regulating motor M-1 and the primaries of synchro control transformers CT-1, CT-2 and CT-3. The T-6 voltages produce the safe signal which causes the receiver-regulator to rotatably drive the fuse to the "safe" position thereof through the sequence of course, and fine control. The fuse is driven into synchronism with the fixed "safe" signal, regardless of the fuse setting order transmitted from the computer. Following safe-setting of the fuse, the projectile may be removed from the cradle for storage.

25 Obviously, many modifications and variations of the present invention are possible in the light of the above teaching. It is therefore to be understood that within the scope of the appended claims the invention may be practiced otherwise than specifically described.

30 The invention described herein may be manufactured and used by or for the Government of the United States of America for governmental purposes without the payment of any royalties thereon or therefor.

What is claimed as new and desired to be secured by Letters Patent of the United States is:

1. A fuze setting system adapted for use with the projectile cradle of a major caliber gun ammunition handling system comprising, a fuze pot assembly adapted for mounting within the cradle in a position for engagement with the nose of a projectile, a receiver-regulator control means adapted for mounting on the exterior of the projectile cradle and adapted for mechanical connection to operatively drive the elements of the fuze pot, said fuze pot including a holding cup for holding the projectile during fuze setting operation and a setting cup means adapted for engagement with the fuze ring of a projectile nose, a fuze pot retracting mechanism connected to the fuze pot assembly and for slidably moving the fuze pot from a position wherein it is engageable with the projectile nose to a retracted position with respect to the projectile nose position in the cradle, and for use when it is desired to handle ammunition in the cradle other than of a fuze-set variety, said retract means comprising a handle, a linkage means between the handle and the fuze pot, and a switch control means engageable with the linkage of the fuze pot retracting mechanism and connected in the circuit of the receiver-regulator to initiate and render the receiver-regulator active when the fuze pot is moved to and maintained in a position for engagement with a projectile in the projectile cradle and further disposed to render the control circuit of the receiver-regulator inactive when the handle of the retract mechanism is moved from the projectile fusing position to the disengaging position for the fuze pot.

2. A fuze pot assembly for setting the fuses of major caliber nose-type fused ammunition in the cradle of a projectile handling system, which fuze pot assembly comprises, a projectile fuze holding cup, a fuze setting cup, a fuze holding dog and a fuze setting dog respectively in each of the said cups, a gear assembly including a differential mechanism connected respectively in operative relationship between the dog of the holding cup and the dog of the setting cup to provide counter-directional concurrent drive for initial dog rotation and adapted after engagement of the holding dog with a mating portion of

the fuze for positive selective rotational drive only of the fuze setting dog, a fuze pot drive assembly comprising an adjustable input coupling connection from a receiver-regulator type drive, a gear type drive means connected from the said input coupling connection to the fuze pot, a gear type driving connection therein from the input of the said gear means to a ring gear element thereof in the fuze pot, a pair of spider gears mounted within the ring gear and arranged in driving engagement with a mating pair of annular bevel gear elements to drive the setting assemblies of the fuze pot, said fuze holding cup being integral with a lower bevel gear element driven by the said spider gear, the upper bevel gear being integral with an annular bevel gear similar thereto and in axial opposed relationship therewith, a pair of translatorily fixed bevel spider gears rotatively mounted in diametrically opposed relationship and fixed with respect to the annular bevel gear in a manner to be driven by the upper annular bevel gear element thereof, an additional beveled ring gear having a hub element thereon connected to drive the fuze setting cup of the fuze pot assembly, the arrangement of said translatorily fixed bevel gears being such as to prevent rotation of the differential elements in an unidirectional rotation when the driving force is through the normal driving means, said fuze pot drive assembly including a slideable drive connection, a fuze pot retracting mechanism connected to the fuze pot assembly and adapted to slideably move the fuze pot from a position wherein it is engageable with the projectile nose to a retracted position with respect to the projectile nose

5 10 15

UNITED STATES PATENT OFFICE
CERTIFICATE OF CORRECTION

Patent No. 2,792,759

May 21, 1957

Ernest F. Campbell et al.

It is hereby certified that error appears in the above numbered patent requiring correction and that the said Letters Patent should read as corrected below.

In the drawings, Sheet 10, Figure 10, the following correction should be made:

The conductor, connected to capacitor C-11 and crossing the junction of capacitor C-10 with capacitor C-12, is electrically connected to this junction.

The ungrounded terminal of resistor R-35 is electrically connected to the junction of resistor R-33 with resistor R-34.

The junction between capacitor C-19 and resistor R-29 is electrically connected to the junction between resistors R-31 and R-32.

The reference character of the unlegended resistor in series with resistor R-29 is R-36.

Resistor R-52 is connected in series relation with resistors R-36 and R-29.

The conductor, legended B-2 and leading away from capacitor C-2, is connected to the junction of resistor R-44A with choke coil CH-2.

Signed and sealed this 13th day of August 1957.
